*J. Loving,
Cotton Press.*

N° 19,571.

Patented Mar. 9, 1858.

UNITED STATES PATENT OFFICE.

JOSEPHUS LOVING, OF MOSCOW, TENNESSEE.

IMPROVEMENT IN COTTON-PRESSES.

Specification forming part of Letters Patent No. 19,571, dated March 9, 1858.

To all whom it may concern:

Be it known that I, JOSEPHUS LOVING, of Moscow, in the county of Fayette and State of Tennessee, have invented a new and Improved Press for Compressing Cotton, Hay, and other Substances or Articles into Bales; and I do hereby declare that the following is a full, clear, and exact description of the same, reference being had to the annexed drawings, making a part of this specification, in which—

Figure 1 is a horizontal central section of my improvement. Fig. 2 is a longitudinal vertical central section of the same.

Similar letters of reference indicate corresponding parts in the two figures.

This invention relates to an improvement in that class of presses in which a progressive power is obtained; and it consists in the peculiar means employed for actuating the follower, whereby a progressive power is not only obtained by a very simple means, but the small amount of friction attending the operating or moving of the follower gradually diminished as the leverage power is increased, the several parts so operating as to render this class of presses much more effectual than usual.

To enable those skilled in the art to fully understand and construct my invention, I will proceed to describe it.

A represents the press-box, which is fitted in a strong horizontal framing, B, constructed in any suitable way.

C represents the follower, which is fitted and works within the press-box. The follower is constructed in the usual way and has a bar, E, attached to it, said bar passing through one end of the press-box and having three rollers, a a b, fitted in its outer end, said rollers being allowed to turn independently of each other.

To the outer end of the follower-bar E two metallic straps, c c, are attached, one to the upper and the other to the lower side of the rod. The outer ends of these straps are connected by a rod, d, which serves as an axis for three rollers, e e f, all of which are shown in Fig. 2. The straps c c, attached to the follower-rod at one end and connected at the opposite end by the rod d, form a link or loop through which two levers, F G, pass. These levers are crossed, or one lever, F, has an oblong opening or slot made in it, through which slot the other lever, G, passes. The inner sides of the two levers F G are faced for a requisite

distance with metal plates g g, and the lever F, as the follower D is forced inward, bears against the two rollers a a, while the lever G bears against the central roller, b. The inner ends of the levers F G have straps h attached, said straps passing around cylindrical shafts i i, placed at the end of the press-box A in the framing B, one at each side. (See Fig. 1.)

The operation is as follows: The follower D is drawn outward at one end of the press-box A by moving the outer ends of the levers F G toward each other, the lever F bearing against the two rollers e e, and the lever G against the central roller, f. When the follower D is moved outward its full length, the cotton or other material to be compressed is placed within the press-box A, the doors C being opened, and when the requisite quantity is placed within the press-box the doors C are closed and the outer ends of the levers F G are moved outward from each other, as indicated by the arrows 1, and the lever F bears against the rollers a a, and the lever G against the central roller, b, in the outer end of said bar. It will be seen that as the levers are moved in the direction alluded to—viz., in the direction indicated by arrow 1—the speed of the follower D will gradually diminish as it is forced inward and compresses the cotton or other substance within the press-box, and as the speed diminishes the power of course increases in a corresponding degree. This is evident, for as the follower is forced inward the distance between the fulcra of the levers on the shafts i and the bearing-points of the levers F G against the rollers a a b gradually decreases, and consequently the lever-power correspondingly increases. It will also be seen that as the lever-power increases the bearing of the levers F G against the rollers a a b becomes more direct, so much so that before the substance in the press-box is fully compressed said rollers are not rotated or their movement is quite inappreciable. The rollers, therefore, when rotated by the levers during the first portion of their movement, diminish friction, and when their services in this respect are not required they remain dormant, there being comparatively no appreciable friction to overcome during the latter part of the movements of the levers.

I would remark that, if desired, the outer ends of the levers F G may be provided each with a wheel fitted on a curved or segment

track or rail, and that the power may be applied to the levers F G in any proper manner.

By this improvement it will be seen that a progressive power is obtained by a very simple arrangement of means, speed being obtained when power is not required, and speed sacrificed and power obtained when power is required.

I do not claim, broadly, so operating the follower of the press that a progressive or variable power is obtained, for various plans have been devised for effecting this purpose; but

I claim as new and desire to secure by Letters Patent—

The peculiar means employed for thus operating the follower—to wit, the crossed levers F G, in combination with the rollers *a b* and *eef*, attached, respectively, to the follower-bar *E* and straps *cc*—substantially as herein shown and described.

JOSEPHUS LOVING.
